UNITED STATES PATENT OFFICE.

DANTE BERTINI, OF BOSTON, MASSACHUSETTS, ASSIGNOR TO THE WALTER M. LOWNEY COMPANY, OF BOSTON, MASSACHUSETTS, A CORPORATION OF MASSACHUSETTS.

CENTER FEEDER.

Application filed March 17, 1920. Serial No. 366,569.

To all whom it may concern:

Be it known that I, DANTE BERTINI, a subject of Victor Emmanuel, King of Italy, residing in Boston, in the county of Suffolk 5 and State of Massachusetts, have invented a new and useful Improvement in Center Feeders, of which the following is a specification.

My invention relates to mechanism for feeding centers to chocolate-coating machines, though it may have other uses. The centers are made of sugar and other materials and are moulded, usually with a flat bottom surface, and it is desirable to 10 present these centers to the coating machine in which they are coated with chocolate or otherwise, resting on these bottom surfaces. Heretofore they have been so presented by placing them in proper position on a feeding 15 conveyor by hand, this service requiring the employment of a number of attendants who handle each center separately, placing it in proper position on a belt conveyor by 20 which it is carried to the coating machine. 25 Machines have been used for this purpose but not satisfactorily. The purpose of my invention is to do this work automatically so that a single attendant only may be required to a machine.

30 My invention will be understood by reference to the drawings, in which it is shown in its preferred form.

Fig. 1 is a plan view of such a machine. Fig. 2 is a side elevation thereof.

35 Fig. 3 is a cross section on line 3—3 of Fig. 4, and

Fig. 4 is a longitudinal section on line 4—4 of Fig. 1.

A, A¹ are supports for the frame on which 40 the moving parts are mounted. In the support A¹ is mounted a pulley A² over which runs the conveyor belt a, the power shaft for this conveyor not being shown.

In the sides A³ of the frame are mounted 45 two sets of guideways b and c for the rapidly reciprocating or jigger tables B and C.

D is a hopper which is mounted between the sides A³ of the frame. It has an opening at its bottom adapted to be closed by 50 the gate E. The gate E slides in ways e in the sides A³ of the frame and is moved to open or close the mouth of the hopper by a rod E¹ connected to a handle lever E² pivoted on the crossbar A⁴. It will be seen that 55 by moving the handle lever E² the gate may

be opened or closed. A spring e¹ keeps it normally in closed position.

In the support A are mounted two cams F, G, their shafts carrying pulleys F¹, G¹ which are belted together by the belt B¹. 60 The pulley F¹ has a wide face and in addition to the belt B¹ carries the belt B² which connects with a power shaft (not shown).

Each cam has a groove f, g, and in each groove runs a cam roll f¹, g¹ carried on the 65 end of a link f², g². The link f² connects with the under reciprocating table B and the link g² with the upper reciprocating table C, and the diameter of the grooves g is such that the table B is given a more rapid 70 reciprocation than that of the table C.

The upper surface of the table B comprises a smooth slightly slanting section b¹ and a section comprising longitudinal grooves which taper at the end as at b², and 75 serve as passages to separate the centers as they are led to the conveyor a. The upper surface of the table C has a crosswise section or depression c¹ which leads up to a crosswise rib c² which separates it from a second 80 concave section or depression c³ from which passages c⁴ lead through a broken crosswise rib c⁵ to a flat section c⁶ which slopes down to the edge c⁷ of the table. The portion of the rib c⁵ between the passages c⁴ slopes up 85 and down both fore and aft between the recesses c³ and the section c⁶ and also laterally to the passages c⁴. Thus a number of opportunities are given to the center to be tumbled about and finally, because its center of gravity is low, to land on its flat bottom.

The hopper D has a flexible edge d preferably made as shown of a piece of cloth or canvas doubled back on itself and located to 95 prevent the crushing of a center as the gate is closed.

In practice the centers are thrown into the hopper, and the tables B and C are rapidly reciprocated, the table B reciprocating 100 or shaking somewhat faster than the table C. The gate E is then opened so that the centers fall onto the table C and because of the rapid reciprocation and sloping surface of the table C, move along thereon toward 105 its front edge, riding up and tumbling over the rib c² or other obstacles and either through one of the passages c⁴ or over one of the sections of the rib c⁵ from which they fall down onto the section c⁶ from which 110

they travel down toward its edge c^7 and onto the table B. By the more rapid reciprocation of the table B they are moved along and off that table through the grooves b^2 and are delivered on their flat surfaces and in straight lines on the conveyor belt.

It will be seen that the tables B and C both slant toward their front edges so that the centers tend to move forward rather than backward, and owing to the general shape of the centers their path of travel and their tumbling causes them to land on their flat bottoms before they are discharged onto the conveyor.

I do not mean to limit my invention to the precise construction shown, its novelty so far as I know lying in a means for so tumbling the centers that they are automatically delivered bottom side down to the coating machine.

The essentials of the invention are, means to feed the centers to one or more jigger tables and cause their movement in a direction toward the conveyor belt and obstacles on the jigger tables to cause centers to tumble and land eventually in a predetermined position, with the addition of desirable means for aligning them so that they will be delivered in convenient position to be handled by the coating machine.

By "centers" I do not mean necessarily sugar centers to be covered with chocolate but any other articles, edible or not, to which a viscous or other coating is to be applied.

What I claim as my invention is:—

1. In a machine of the kind described, a feeding means and a rapidly reciprocating jigger table located below said feeding means to receive centers therefrom, means to reciprocate said jigger table, and means located on said jigger table comprising crosswise ribs adapted to tumble the centers and cause them to be delivered therefrom in a predetermined position, the upper surface of the jigger table being at a slight angle to the horizontal from its receiving to its delivery end.

2. In a machine of the kind described, a center feeding means, a jigger table one end of which is located to receive centers therefrom, and means for reciprocating it, the upper surface of said jigger table slanting slightly from its center-receiving end to its delivery end and being provided with obstacles adapted to cause said centers to be

tumbled on their passage from one end of the jigger table to the other, said obstacles comprising a cross rib and a broken cross rib having ends sloping down to the normal level of the table to form passages into which the material fed may be delivered either progressively from the rear end of the table or laterally from the sloping ends of the broken ribs and from which they will be delivered towards the front end of the table.

3. In a machine of the kind described, a center-feeding means, two jigger tables, means for reciprocating them at different speeds, the more rapidly reciprocating table being located to receive centers from said receiving means, the other jigger table being located to receive centers from said first-named jigger table, the upper surface of both of said jigger tables slanting slightly from their receiving to their delivery ends and said first-named jigger table being provided with obstacles comprising cross ribs adapted to tumble said centers as they are shaken from the receiving to the delivery end thereof.

4. In a machine of the kind described, a center-feeding means, two jigger tables, means for reciprocating them at different speeds, the more rapidly reciprocating table being located to receive centers from said receiving means, the other jigger table being located to receive centers from said first-named jigger table, the upper surface of both of said jigger tables slanting slightly from their receiving to their delivery ends and said first-named jigger table being provided with obstacles comprising cross ribs adapted to tumble said centers as they are shaken from the receiving to the delivery end thereof, and said second table being provided with means whereby the centers will be delivered therefrom in predetermined positions.

5. In a machine of the kind described, two jigger tables, one overlapping the other, and means for reciprocating them at different speeds, one of said tables having crosswise ribs and the other longitudinal ribs, a hopper located to feed material to one of said jigger tables, a gate adapted to close the lower end of said hopper, said hopper having a flexible edge located to prevent the crushing of the material being fed upon the closing of the lower end of the hopper.

DANTE BERTINI.
